UNITED STATES PATENT OFFICE.

JAMES CLAYTON, OF NEW YORK, N. Y.

APPARATUS FOR RAISING LIQUIDS.

SPECIFICATION forming part of Letters Patent No. 658,941, dated October 2, 1900.

Application filed September 23, 1898. Serial No. 691,687. (No model.)

To all whom it may concern.

Be it known that I, JAMES CLAYTON, a citizen of the United States, and a resident of the borough of Brooklyn, in the city of New York and State of New York, have invented a new and useful Improvement in Apparatus for Raising Liquids, of which the following is a specification, reference being had to the accompanying drawings.

10 This invention relates to apparatus such as are variously known as "pneumatic water-lifts" and "compressed-air pumps" for raising water by the direct pressure upon it of air or gas having a pressure greater than that of the atmosphere.

Figure 1 in the drawings represents an elevation, partly in section, of an apparatus embodying my invention. Fig. 2 is a plan of the pressure-tank and of the pipes and valves 20 for the induction of the compressed air or gas thereto and the eduction of said air and of the liquid therefrom, the pipes being shown partly in section. Figs. 3 and 4 represent elevations, partly in section, of parts of the 25 pressure-tank and of the reservoir or well in which it is placed and of certain of the pipes and valves and of the valve-operating mechanism, showing the latter mechanism in two positions. Figs. 5 and 6 are vertical sectional 30 views of portions of the air-pipes and of a three-way valve therein, showing the latter in different positions.

Similar letters of reference designate corresponding parts in all the figures.

35 A designates a well, reservoir, or any source wherein the water or liquid to be elevated is contained and in which is placed the closed pressure-tank B, which receives therefrom the water to be elevated and which receives 40 from an air-reservoir C the compressed air or gas by the pressure of which the said water or liquid is elevated, said air or gas being supplied by any suitable means, as by a compressor D, the delivery-pipe D' of which connects with the said reservoir C. I will hereinafter speak of said liquid as "water" and of said air or gas as "air."

The pressure-tank is furnished at or near its bottom with inlet-valves *a* of any suitable 50 kind which will open automatically when the pressure in said tank is less than that due to the column in the well or reservoir A and

will close when the pressure in said tank is greater than that of said column. The said tank is connected at its top with the air-reservoir C by a pipe E, through which, under the control of a three-way cock F, as will be hereinafter described, air is supplied from said reservoir to said tank for expelling the water from the latter through the discharge-conduit G, the inlet of which is at *b* near the bottom of the tank and which runs to any point at which the water is to be delivered. The said pipe E has a branch E', which connects with the inlet of the compressor and 65 which constitutes the suction-pipe thereof and which is controlled by the valve F, hereinbefore mentioned, which is at the branching of the two pipes. In the suction-pipe E' there is an opening or branch E² for communication with the atmosphere. At the mouth of this opening or branch there is an ordinary check-valve E³, arranged to open inwardly and close outwardly, as will be hereinafter described.

75 By the three-way cock at the branching of the pipe E' from E communication may be made directly through the pipe E from the air-reservoir C to the pressure-tank B, as shown in Fig. 5, while communication between said pipe and the suction-pipe E' of the compressor is closed, or communication may be made, as shown in Fig. 6, through said pipe E between the tank B and the suction-pipe E' of the compressor while communication between the air-reservoir and pressure-tank is closed. Said cock is operated by mechanism actuated by a float I in the pressure-tank, said mechanism consisting of a longitudinally-moving rod J, which passes through 80 a stuffing-box *c* in the top of the tank, and connections between said rod and the arm *j* on the valve-spindle *k*. Said rod works in a guide *d* on the bottom of the tank and a guide *d'*, attached to the pipe E, and the said float 85 is capable of sliding freely on it between two collars *e e'* thereon. The said rod is connected by short links *f* with the forked lower arm of an elbow-lever K, which works on an independent fixed fulcrum *h* above the tank and 90 which is also connected by rods *i* with a forked arm *j* on the valve-spindle *k*. The upper arm of said elbow-lever has attached 95 to it a tumbler-box *l*, the bottom of which

forms a reversible inclined plane and which contains a ball or rolling weight m , which rolls to one or the other end of said box as the upper arm of the lever in its movement passes 5 a vertical position and causes the reversal of the inclination of the bottom of said box.

The operation of the apparatus is as follows: First supposing the tank B to be empty and the float I on the collar e of the valve-rod 10 J, as shown in Fig. 1, holding said collar down on the guide d , the said rod then by its connections f and i with the valve F holds the latter in the position indicated in Fig. 6, shutting off the air-reservoir C from the tank 15 and leaving the suction-pipe E' open to the tank. Water now enters the tank through the valves a , and as it rises therein, expelling the air therefrom through the pipes E and E' to the inlet of the compressor, it raises the 20 float. When the tank becomes nearly full of water, the float reaching the collar e' pushes up the valve-rod, which then, acting through the connections f i , begins to move the valve slowly toward the position shown in Fig. 5, 25 at the same time moving the tumbler-lever K until it passes its line of culmination and the bottom of the tumbler-box passes the horizontal position and assumes the slightest inclination, when the weight m quickly runs 30 down said box and throws the lever over to the position shown in Fig. 4, producing very suddenly the completion of the movement of the valve to cut off communication between the tank and the suction-pipe of the 35 compressor and open communication between the air-reservoir and the tank, which then begins to discharge its water through the conduit G. The float then descending and coming on the collar e of the valve-rod operates as a weight 40 and pulls down the rod, which then begins to move the valve slowly toward the position shown in Fig. 6, at the same time moving the tumbler-lever until the box l passes its point of culmination and reverses the inclination 45 of the bottom of the tumbler-box, when the weight rapidly produces the further movement of the lever to the position shown in Fig. 3 and throws the valve quickly to the position shown in Fig. 6, thus opening communication 50 between the tank and the suction-pipe of the compressor and permitting the discharge of the air from the tank into the compressor.

It will be obvious that by the connection 55 of the suction-pipe of the air-compressor with the pressure-tank, as described, whereby the

air which has done its work and which may yet have a pressure greater than that of the atmosphere is returned to the compressor instead of being allowed to escape to the atmosphere, a very considerable economy of power may be effected. It is, however, possible that with such connection there may be by reason of leakage or other cause a deficient supply of air to the compressor, and it is to make up 60 any such deficiency that I provide in the so-connected suction-pipe the opening E² with the check-valve E³, which opens to permit air from the surrounding atmosphere to enter to supply any deficiency, but closes to prevent 65 any waste of air at a pressure above that of the atmosphere.

The valve-operating mechanism herein described might be used in an apparatus in other respects like that described, but in which the 70 pipe E' for the escape of the spent air from the pressure-tank might have no connection with the compressor, but which would permit the escape of said air to the atmosphere.

What I claim as my invention is— 80

In an apparatus for raising liquids, the combination of a pressure-tank provided with valves for controlling the entrance of liquid thereto and with a liquid-discharge conduit, a reservoir for compressed air or gas, a pipe 85 between said reservoir and tank for the passage of the compressed air or gas from said reservoir to said tank, a compressor for supplying the compressed air or gas to said tank, a pipe branching from the first-mentioned 90 pipe and constituting the suction-pipe of the compressor for returning to the compressor the spent air or gas from the tank, a three-way cock at the branching of said pipes, an arm on the spindle of said cock, a float in the 95 pressure-tank, a rod actuated by said float, a tumbler-lever and an independent fixed fulcrum therefor, connections between said tumbler-lever and rod and between said lever and the arm on the cock-spindle, an inlet from 100 the atmosphere to said suction-pipe and an outwardly-closing check-valve at said outlet, all substantially as and for the purpose herein described.

In testimony that I claim the foregoing as 105 my invention I have signed my name, in presence of two witnesses, this 20th day of September, 1898.

JAMES CLAYTON.
